H. Narimore,

Farm Implements

Patented Nov 24, 1834.

Horace McCormick. (Caledonia N. York)

Letter Patent Nov. 24. 1834.

The Schedule referred to in this Letter Patent and making part of the same containing a description in the words of the said Horace McCormick himself of this improvement in the form of the scythe for cutting grain & grass.

To all to whom these presents shall come.

I, Horace McCormick of Caledonia in the County of Livingston and State of New York have invented a new and useful improvement consisting in an improvement in the form of the scythe for cutting grass and crops and the following is a full and exact description of the same as improved by me - The length of the said scythe 4 feet. The width in the widest part 14 inches differing from the scythes already known and in common use in the following particulars. first in more circular in form. and the majority of the blade being at the heel and of the scythe instead of at the point recusing of it from the usual method. Those made for cutting grass when connected with the grass cradle. The heel is recused from the common method which is a considerable convenience in fastening the scythe to the mouth of the cradle. The same form of scythe is recommended for cutting grass with the following exceptions. The scythe should be made narrower and shorter so as to be held to the common grass as to these particulars. also the heel is in the same way as in the scythe already known. I could repeat that the scythe in both instances may be advantageously connected to the cradle by means of a cruse. What I claim as my invention is distinguishing the scythe as above described together with the method of connecting them to the cradle by means of a cruse. I do not confine my improvement to any particular width or breadth but I claim the privilege of manufacturing and selling to any consequent size which shall prove of the greatest utility.
